(57) **CLAIM**

The ornamental design for a cable trough, as shown and described.

DESCRIPTION

FIG. 1 shows a top isometric view of the assembled cable trough;

FIG. 2 shows a top view of the assembled cable trough;

FIG. 3 shows a bottom view of the assembled cable trough;

FIG. 4 shows a left side view of the assembled cable trough;

FIG. 5 shows a right side view of the assembled cable trough;

FIG. 6 shows a front view of the assembled cable trough;

FIG. 7 shows a rear view of the assembled cable trough;

FIG. 8 shows an exploded view of the cable trough;

FIG. 9 shows a top view of the base of the cable trough;

FIG. 10 shows an end view of the base of the cable trough;

FIG. 11 shows a top isometric view of the base of the cable trough;

FIG. 12 shows an underside of the lid of the cable trough;

FIG. 13 shows a side view of the lid of the cable trough;

FIG. 14 shows an end view of the lid of the cable trough;

FIG. 15 shows an isometric view of the underside of the lid of the cable trough;

FIG. 16 shows a top view of the divider of the cable trough;

FIG. 17 shows a side view of the divider of the cable trough;

FIG. 18 shows a bottom view of the divider of the cable trough;

FIG. 19 shows an end view of the divider of the cable trough;

FIG. 20 shows an isometric view of the top of the divider of the cable trough; and,

FIG. 21 shows an isometric view of the bottom of the divider of the cable trough.

The broken lines shown represent portions of the cable trough that form no part of the claimed design.
